UNITED STATES PATENT OFFICE.

LOUIS V. ARONSON, OF NEWARK, NEW JERSEY.

LIQUID-DROPPER.

1,399,916.

Specification of Letters Patent. Patented Dec. 13, 1921.

Application filed June 22, 1921. Serial No. 479,561.

To all whom it may concern:

Be it known that I, LOUIS V. ARONSON, a citizen of the United States, residing at Newark, in the county of Essex and State 5 of New Jersey, have invented certain new and useful Improvements in Liquid-Droppers, of which the following is a specification.

This invention relates to droppers, and 10 has as an object the provision of a device which may be applied to the neck of a bottle, and whereby liquid may be poured from a bottle into a small opening a few drops at a time if desired, without the liquid being 15 permitted to run back down the neck of the bottle.

An illustrative embodiment of the invention is shown in the accompanying drawings, in which

20 Figure 1 is a vertical section showing a bottle and a tube in dotted lines;

Fig. 2 is a plan view and

Fig. 3 is an end view, as seen from the right side of Fig. 2.

25 As shown, the device comprises a substantially semi-spherical portion 10 having a spout portion 11 secured to an opening 12 in the center thereof.

To allow the device to roughly fit against 30 the neck of a bottle, a portion of its surface is cut away, as shown at 13. To secure the device to bottles of varying sizes a divided ring 14 is secured to the lowest part of the cut away portion 13 and the ends 15 of said

ring are preferably turned outward to provide for the ready slipping of the open portion of the ring over the neck of a bottle.

A convenient means of attaching the ring to the portion 10 is shown in Fig. 1, wherein a strip 16 is turned outward from the material of the funnel portion 10 and bent about the ring, as at 17. Preferably the strip 16 is soldered to the ring where it embraces the same.

Due to the small opening in the spout 11 45 fluid may be poured into a very small tube, such as a fountain pen, or the neck of a vial, and will be prevented from running back down the neck of a bottle.

Minor changes may be made in the physical embodiment of the invention without departing from its spirit.

I claim:

1. A tube comprising a funnel portion having a cut away portion to approximately 55 fit the same to the neck of a bottle, an outlet from said funnel portion, and means to secure the device closely adjacent the lip of a bottle.

2. A tube comprising a funnel having a 60 cut away portion, a split ring secured to said funnel adjacent the said cut away portion, said ring adapted to be slipped about the neck of a bottle, and an outlet from said funnel portion.

In testimony whereof I affix my signature hereto.

LOUIS V. ARONSON.
